UNITED STATES PATENT OFFICE

152,626

DESIGN FOR A PANEL FOR AN ELECTRONIC TIMER OR SIMILAR ARTICLE

John William Lauricella, Passaic, N. J.

Application November 7, 1946, Serial No. 134,572

Term of patent 14 years

(Cl. D26—1)

To all whom it may concern:

Be it known that I, John William Lauricella, a citizen of the United States, residing in Passaic, in the county of Passaic, in the State of New Jersey, have invented a new, original, and ornamental Design for a Panel for an Electronic Timer or Similar Article, of which the following is a specification, reference being had to the accompanying drawing, forming part thereof.

Fig. 1 is a plan view of a panel for an electronic timer or similar article, showing my new design.

Fig. 2 is a top plan view of Fig. 1.

The characteristic features of my design reside in the portions shown in full lines.

I claim:

The ornamental design for a panel for an electronic timer or similar article, as shown and described.

JOHN WILLIAM LAURICELLA.
